CONCRETE FORM PANEL AND CLAMP
THEREFOR

Arthur J. Harder, Chicago, Ill.

Application June 25, 1947, Serial No. 756,968

6 Claims. (Cl. 25—131)

1

The present invention relates to clamps for cement form panels, its objects being substantially the same as specified in my co-pending application, filed April 4, 1947, Serial No. 739,309, now Patent No. 2,461,738.

A further object of the present invention is to simplify the construction of a clamp, whereby the panels and the tie may be interlocked and maintained in a rigid mutual relation during the erection of a concrete wall.

A still further object of the present invention is the provision of a clamp capable of engaging and interlocking a pair of panels with a tie in various angular positions of the latter with respect to the panels.

Another object of the present invention is the provision, in combination with a plurality of cement form panels having angle members affixed thereto adjacent their marginal portions, with ties interposed between the margins of adjacent panels and the adjacent angle members, of a suitable clamp capable of simultaneously engaging the tie and a pair of the adjacent angle members.

A further object of the present invention is the provision in a clamp of the type indicated of means for rendering the clamp capable of angular adjustment with relation to the tie and to a pair of adjacent angle members.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application and in which like designating characters refer to corresponding parts throughout the several views:

Fig. 1 is a transverse cross-sectional view of the clamp illustrating its operative position with the panels and the tie for holding them in a mutually interlocked rigid position;

Fig. 2 is a cross-sectional view of the clamp on line 2—2 of Fig. 1;

Fig. 3 is the elevational view rearwardly of the panels with the present clamp in an operative position vertically of the panel joint;

Fig. 4 is a top elevational view of the present clamp; and

Fig. 5 is a side elevational view of the clamp.

Referring to the present drawing there is shown a pair of panels 10 in an edge to edge position. Such panels are employed for erecting

2

a pair of spaced form walls, between which cement mixture is poured for making a concrete wall. A plurality of ties 11 is positioned within the space defined by a pair of form walls. The 5 ends of the ties are interlocked with the panels for maintaining a pair of form walls in a rigid spaced relation.

Each panel along its edges is provided with a plurality of complementary recesses 12. When 10 a pair of panels 10 is placed in an edge to edge position recesses 12 will form an oblong slot 13 for extending therethrough tie 11. Each of panels 10 is further provided along its margin with angle member 14, which is affixed by its 15 base to the body of the panel, and the remaining portion of which forms a vertical leg portion. Said angle member 14 is spaced from the edge of panel 10 for providing clearance for recess 12, and for accommodating between two 20 angle members 14 in a pair of cooperating panels 10 said tie 11.

The clamp constituting the subject-matter of this application includes a block or body portion 15 of substantially rectangular formation. Said 25 body portion 15 along one of its narrower ends is provided with a central recess 16 for effecting a pair of spaced jaws 17, which remain in a mutually rigid relation. Each of said jaws 17 on its inner face and along its free end is provided 30 with bead 18. The two opposed beads in two jaws 17 are spaced to the extent corresponding to the width of a pair of vertical leg portions of said angle member 14, with tie 11 interposed therebetween, as seen in Fig. 1 and within which 35 said vertical leg portions of angle members 14 snugly fit.

Extending from the outer face of one of said jaws 17, and in a perpendicular relation therewith, is boss 19 provided with a central threaded bore for receiving in a threaded engagement 40 screw 20, having head 21. Extended through said head 21, in a transverse relation, is a cross bar 22, by means of which said screw 20 may be rotated in either direction for disengaging the same from said vertical leg portions of angle members 14 or for bearing thereagainst for holding a pair thereof with the interposed tie 11 in a firm clamped relation.

Formed in the body portion 15 of the clamp 50 is recess 23 of trapezoid formation, the wider end of which communicates with recess 16. Said recess 23 is centrally of body portion 15 of the clamp both on horizontal and vertical planes thereof. Said recess 23 is also in a central relation with recess 16, and has the width substan-

tially corresponding to the thickness of tie 11, and within which the end of the latter is receivable, as is seen in Fig. 1. The trapezoid formation of said recess 23 permits various angular adjustments of tie 11 within said recess 23, as is indicated by dotted lines in Fig. 2.

Made in the body portion 15 of the clamp, and in a transverse relation with recess 23 is aperture 24. Tie 11 at its ends is provided with similar apertures, one of which registers with aperture 24, for receiving pin 25 therethrough when the clamp is in an operative position with tie 11. By this arrangement tie 11 is bound to the clamp, and when two clamps are engaged to tie 11, one at each end thereof, the latter will be capable of holding a pair of spaced panel form walls in a rigid relation, preventing shifting thereof under the pressure of the poured cement mixture between the form walls.

Communicating with said recess 23 and extending through the adjacent end of body portion 15 of the clamp is recess 26 of substantially rectangular formation and of the width on transverse cross-section corresponding to that of recess 23. That recess 26 is designed for receiving therewithin ties longer than ties 11, and narrower than the latter. If such ties are snugly fitted within recess 26 no angular adjustment thereof will be possible. If however such ties are narrower on horizontal plane of the clamp than recess 26 some angular adjustment thereof will be possible.

From the hereinabove description it will be readily seen that the clamp herein disclosed binds a pair of adjacent panels in a coplanar relation thereof, by rigidly engaging the vertical leg portions of angle members 14, thereby permitting erection of a form wall from said panels 10 when the latter are laid in an edge to edge position. Simultaneously the clamp clamps tie 11 to a pair of panels 10 by rigidly engaging the former with said vertical leg portions of angle members 14, which is accomplished through jaws 17 and screw 20, and lastly the clamp rigidly engages tie therewith through the medium of pin 25 thereby preventing shifting of a pair of panel form walls to or away from each other.

When a concrete wall has been erected the clamp is removed from panels 10 and ties 11 by loosening screw 20 and withdrawing pin 25 from aperture 24. This will disengage the clamp from panels 10 and ties 11, and thereupon panels 10 may be readily removed from the faces of the concrete wall. The ends of ties 11 projecting from the faces of the concrete wall may be broken off as shown in my said co-pending application.

The occasion for angularly adjusting the clamp with relation to tie 11, and accommodating the latter in its angular adjustments within recess 23, arises when the form walls are erected at an incline. In that instance ties 11 cooperating with the vertical angle members 14 will not be in a perpendicular relation with the said angle members or with their panels, but will remain in an oblique relation therewith. This necessitates angular adjustment of the clamp with relation to tie 11, and the trapezoid form of recess 23 permits such an adjustment.

While there is described herein a preferred embodiment of the present invention, it is nevertheless to be understood that minor changes may be made therein without departing from the spirit and scope of the invention as claimed.

What I claim as new is:

1. In the art of binding a pair of concrete wall form panels, each of said panels being provided on its margin with an angle member, the outwardly extending leg portion of said angle member in each panel being substantially in a perpendicular relation with the body of the panel, with a wall form retaining tie passed between the margins of a pair of adjacent panels and between a pair of adjacent leg portions of said angle members in a pair of panels, said tie extending beyond the outer edge of said leg portions of said angle members, a clamp for retaining a pair of said panels in a rigid mutual relation and for binding said tie thereto, comprising a block, a pair of spaced stationary jaws at one end of said block, a pair of adjacent leg portions of said angle members on a pair of panels with said tie interposed therebetween being received between said jaws, means in said jaws for rigidly binding said leg portions and said tie on the transverse plane thereof, said block having a recess therein extending from said jaws lengthwise thereof receiving one end of said tie therein, and means extending transversely through said block and said recess and pivotally engaging the end of said tie.

2. A clamp of the type described adapted to receive a tie, comprising a block, a pair of spaced jaws formed rigidly on one end of said block and extending longitudinally therefrom, said jaws having a recess therebetween, said block having a second recess therein extending transversely from said first-mentioned recess clamping means connected with one of said jaws, and means extending transversely of said block and said second recess for pivotally engaging an end of the tie in said second recess.

3. A clamp of the type described adapted to receive a tie comprising a block, a pair of spaced jaws formed rigidly on one end of said block extending longitudinally therefrom, said jaws having a recess therebetween, said block having a second recess therein extending transversely from said first mentioned recess, a screw member carried by one of said jaws, and a pin extending transversely of said block and said second recess for pivotally engaging an end of said tie in said second recess.

4. A clamp of the type described adapted to receive a tie comprising a block, a pair of spaced jaws formed rigidly on one end of said block extending longitudinally therefrom, said block having a recess therein extending from said spaced jaws substantially to the opposite end of said block, said recess flaring outwardly at the end adjacent said jaws and being adapted to receive a tie therein in swinging relation to said block and said recess, and means extending transversely through said block and said recess adjacent the flaring portion of said recess for pivotally engaging the end of a tie in said recess.

5. In the art of binding a pair of concrete wall form panels, each of said panels being provided on its margin with an angle member, the outwardly extending leg portion of said angle member in each panel being substantially in a perpendicular relation with the body of the panel, with a wall form retaining tie passed between the margins of a pair of adjacent panels and between a pair of adjacent leg portions of said angle members in a pair of panels, said tie extending beyond the outer edge of said leg portions of said angle members, a clamp comprising a block, a pair of spaced jaws at one end of said block, a

pair of adjacent leg portions of said angle members on a pair of panels with said tie interposed therebetween being received by the said jaws, said block being provided with a recess in its body portion extending from said jaws lengthwise thereof for receiving an end of said tie, a pin extending transversely through said block and said recess for pivotally engaging said tie, and means in said block for rigidly interlocking the pair of adjacent leg portions of said angle members in a pair of panels with said tie interposed therebetween on a transverse plane thereof, said recess being outwardly flaring adjacent the jaws for permitting angular adjustment of said block with relation to the tie.

6. In the art of binding a pair of concrete wall form panels, each of said panels being provided on its margin with a member, said member extending substantially in a perpendicular relation with the body of the panel, with a wall form retaining tie passed between the margins of a pair of adjacent panels and between a pair of adjacent leg portions of said members in a pair of panels, said tie extending beyond the outer edge of said leg portions of said members, a clamp for retaining a pair of said panels in a rigid mutual

relation and for binding said tie thereto, comprising a block, a pair of spaced stationary jaws at one end of said block, said pair of adjacent members on the pair of panels with said tie interposed therebetween being received by the said jaws, means in said jaws for rigidly binding said members and said tie on the transverse plane thereof, said block having a recess therein extending from said jaws lengthwise thereof receiving one end of said tie therein, and means extending transversely through said recess and pivotally engaging the end of said tie.
